(57) **CLAIM**

The ornamental design for a tyre tread, as shown and described.

DESCRIPTION

1. Tyre tread

1.1 : Front

1.2 : Left

1.3 : Right

1.4 : Perspective

1.5 : Enlarged

1.6 : Enlarged

1.7 : Cross sectional

1.8 : Cross sectional

1.9 : Cross sectional

1.10 : Cross sectional

Fig. 1.5 is a fragmentary enlarged perspective view surrounded by line 1-1 and line 1'-1' in Fig. 1.1; Fig. 1.6 is a fragmentary enlarged perspective view surrounded by line 2-2 and line 2'-2' in Fig. 1.4; Figs. 1.7, 1.8, 1.9 and 1.10 are cross-section views respectively taken along lines A-A, B-B, C-C and D-D in Fig. 1.5; In the drawings, the pattern repeats uniformly throughout the circumference of the tyre tread, and broken lines depict environmental subject matter only and form no part of the claimed design# All the leader lines, arrows and labels in reproductions 1.1, 1.4, 1.5 form no part of the claimed design.
